UNITED STATES PATENT OFFICE.

JOSEPH WYMORE, OF SEATTLE, WASHINGTON.

PARCEL-POST MAIL-BOX.

1,150,409.

Specification of Letters Patent. Patented Aug. 17, 1915.

Application filed September 15, 1914. Serial No. 861,818.

To all whom it may concern:

Be it known that I, JOSEPH WYMORE, citizen of the United States, residing at Seattle, in the county of King and State of Washington, have invented certain new and useful Improvements in Parcel-Post Mail-Boxes, of which the following is a specification.

This invention relates to improvements in receptacles for mail matter, more particularly to parcels post mail matter, and has for one of its objects to provide a simply constructed receptacle whereby the parcels of the mail matter may be quickly transferred from the receptacle to a car, wagon, or like conveyance, or transferred from the car, wagon, or like conveyance to the receptacle.

Another object of the invention is to provide a simply constructed device which may be tilted and opened to receive mail matter and automatically closed when returned to its normal position.

Another object of the invention is to provide a simply constructed device for receiving the mail matter including a closure and means for holding the same in closed position during the tilting operation to prevent a premature discharge of the contents.

With these and other objects in view the invention consists in certain novel features of construction as hereinafter described and specifically pointed out in the claim.

The improved device may be employed in connection with mail cars, mail delivery and collecting wagons or like vehicles, and it is not desired therefore, to limit the invention to use with any specific conveyance, but for the purpose of illustration the improved device is shown arranged to be employed in connection with a conventional mail car, and in the drawings thus employed:

Figure 1 is a sectional elevation of a portion of a conventional mail car and a vertical section of the mail receiving apparatus arranged in operative relation to the car; Fig. 2 is a perspective view of the improved device; Fig. 3 is a transverse section on the line 3—3 of Fig. 1.

Corresponding and like parts are referred to in the following description and indicated in all the views of the accompanying drawings by the same reference characters.

When employed in connection with the railway mail service, the improved device will be located adjacent to the track over

which the cars pass, so that the mail matter may be conveniently discharged from the receptacle into the car through the usual side door opening, and when employed in connection with the ordinary collection vehicles, the apparatus will be so located that the vehicle may be driven to a point convenient to the device to enable the device to be overturned into the vehicle or into an opening therein. The improved device includes a suitable supporting frame, and for the purpose of illustration the frame and its receptacle is shown located upon the platform 10 convenient to the track, a portion of which is illustrated at 11 with a portion of a conventional mail car indicated as a whole at 12 with one of the side door openings indicated at 13.

The frame which supports the improved apparatus may be of any suitable construction and of any suitable material, but for the purpose of illustration is shown formed of corner posts 14 and an inclined top or closure 15. The posts 14 are supported at suitable intervals by transverse members indicated at 16.

The receptacle for the mail matter comprises a casing represented as a whole at 17 preferably formed of sheet metal and with an angular bottom 18 and hinged closure 19. The receptacle 17 fits relatively close within the posts 14 of the frame and bearing at its lower portion when in vertical position against one of the transverse members 16 which thus forms a stop to limit the movement of the receptacle in one direction as hereinafter explained. Connected to the posts 14 at the front of the supporting frame are ears 20 in which a rod 21 is supported. The receptacle 17 is coupled to the rod 21 by staples or U-bolts 22 or other suitable devices. By this means the receptacle 17 is mounted to swing upon the rod 21 into the position shown by dotted lines in Fig. 1, and supported in vertical position as shown in full lines in Figs. 1 and 2 with the lower portion bearing against one of the transverse members 16 as before stated, to prevent the receptacle from moving beyond the vertical position.

Extending between the rear posts 14 at their upper ends is a transverse member 23 against which the rear lower portion of the casing 17 bears when disposed in its tilted position, as indicated by dotted lines in Fig. 1 to limit the movement of the receptacle.

Attached to the upper front face of the receptacle 17 is a handle bail 24, while another handle bail 25 is connected to the forward edge of the closure 19. The bail 25 is directed downwardly to closely engage the bail 24, as illustrated in Fig. 2, so that the operator may grasp both bails at once and thus hold the closure 19 in closed position at the same time that he is pulling the receptacle into its tilted position, and thus hold the closure 19 in engagement with the upper edge of the receptacle 17 until the latter is disposed in its full tilted position, and thus prevent the premature discharge of the mail matter. A suitable implement such as a hook, indicated at 26, may be employed to pull the receptacle 17 into its tilted position, the hook being engaged with both of the bails 24-25 and holding the closure 19 in engagement with the receptacle as long as required in the same manner as when the device is manually operated. If the receptacle 17 is entirely filled with parcels of mail matter, there would be danger 25 of its escape if the closure 19 were prematurely opened when the receptacle had been tilted into the position shown in Fig. 1, but by providing the coacting members 24-25 the discharge of the receptacle may be readily controlled. This is an important feature of applicant's device, and materially increases its efficiency and utility.

It will be noted that when in closed position the closure 19 is relatively close to the inclined top 15 of the supporting frame. When mail matter is to be deposited in the receptacle the lower bail member 24 is utilized by the person who is to deposit the mail to slightly tilt the receptacle 17 upon its rod 40 21 until a sufficient portion of the receptacle is drawn forwardly to enable the closure 19 to be opened to a sufficient extent to deposit the mail matter, and then when the receptacle is released it will return automatically 45 to its vertical position. The top 15 of the frame, it will be noted, is relatively close to the closure 19 of the receptacle when the

latter is in vertical position, as shown in Fig. 1. Consequently, if the closure 19 is not manually closed or does not fall shut by gravity, the closure 19 will engage the top 15 when the receptacle is moved into vertical position, and thus automatically close the same and protect the contents of the receptacle. This is also an important feature 55 of applicant's device and increases its efficiency and utility.

The coacting members 24-25 may likewise be utilized to receive a padlock or other fastening device if desired. The supporting frame may be movable or stationary, as may be preferred. Two or more of the receptacles may be employed, one to receive outgoing mail, and the other one to receive incoming mail, but it is not deemed necessary to illustrate a duplication of the receptacle.

The improved device may be employed to receive incoming mail by simply tilting the empty receptacle into the position shown by dotted lines in Fig. 1, depositing the mail matter and then releasing the receptacle, when it will be returned automatically by gravity to its closed and vertical position.

Having thus described the invention, what is claimed as new is:

In an apparatus of the class described, a receptacle mounted for swinging movement, a closure for said receptacle, a handle loop connected to said closure, and a handle loop connected to said receptacle, the handle loop of the receptacle being relatively close to the handle loop of the closure when the same is closed so that both handle loops can be grasped by one hand to simultaneously swing the receptacle and hold the closure in position.

In testimony whereof I affix my signature in presence of two witnesses.

JOSEPH WYMORE. [L. S.]
